LOCK SEAM FOR PIPE SECTIONS

William J. Gray, Rochester, N. Y., assignor to
 Gray Metal Products, Inc., Rochester, N. Y., a
 corporation of New York

Application August 21, 1950, Serial No. 180,596

1 Claim. (Cl. 138—74)

1

The invention relates to a lock seam for pipe sections.

An object of the present invention is to improve the construction of lock seams for pipe sections of stove pipes, conduits of air conditioning units, pipes for hot air furnaces and various other conduits, and to provide a simple and comparatively inexpensive lock seam of strong and durable construction formed from a rectangular blank of sheet material and having opposed longitudinal seam edge portions, one of the longitudinal seam edge portions being provided with a groove opening outwardly and having walls arranged at the entrance to the groove closer or of less distance apart than the thickness of the metal of the other plain longitudinal edge portion, whereby when the latter is introduced into the groove the walls thereof will be spread and will frictionally engage the plain longitudinal edge with sufficient force to enable a plurality of pipe sections to be assembled for proper positioning of the assembly without liability of the seam members accidentally opening and prior to locking of the seams after the assembly has been properly adjusted and fitted in the position it is to occupy.

A further object of the invention is to provide a lock seam pipe section of this character having on its seam members coacting interengaging locking means located inwardly of the preliminarily engaged portions so that after the pipe sections of an assembly have been properly positioned the coacting locking devices may be snapped into engagement with each other by pressure applied to the pipe sections at points spaced from the lock seam.

A further object of the invention is to construct and arrange the coacting interlocking devices of the seam members so that upon further relative movement of the seam members toward each other after the preliminary engagement of the same, the resiliency of the walls of the plain edge receiving groove will operate to snap the coacting engaging portions into interlocking engagement.

A further object of the invention is to position the interlocking coacting devices of the seam members adjacent the ends of a pipe section of the standard length and also at intermediate points in proper position so that when pipe sections are cut to provide sections shorter than the standard length, such shorter sections will be provided adjacent their ends with the locking means and the seams of shorter sections will be locked in the same manner and as securely as the seams of standard sections.

2

With the above and other objects in view, the invention consists in the construction and novel combination and arrangement of parts herein-after fully described, illustrated in the accompanying drawings and pointed out in the claim hereto appended, it being understood that various changes in the form, proportions, and minor details of construction, within the scope of the claim, may be resorted to without departing from the spirit of sacrificing any of the advantages of the invention.

In the drawing:

Fig. 1 is a front perspective view of a lock seam pipe section constructed in accordance with this invention, the longitudinal edge portions of the pipe section being spaced apart to illustrate the locking means more clearly;

Fig. 2 is a rear perspective view of the lock seam, the pipe section being sectioned longitudinally from its upper end to a point near its lower end;

Fig. 3 is a view similar to Fig. 2 showing the lock seam closed and the coacting interlocking means of the seam members in engagement with each other;

Fig. 4 is an enlarged detail vertical sectional view taken substantially on the line 4—4 of Fig. 3;

Fig. 5 is an enlarged detail sectional view taken substantially on the line 5—5 of Fig. 2;

Fig. 6 is an enlarged detail sectional view taken on the line 6—6 of Fig. 3;

Fig. 7 is an enlarged detail sectional view taken approximately on the line 6—6 of Fig. 3 with the seam members preliminarily engaged and with the coacting locking devices out of engagement with each other.

In the accompanying drawing in which is illustrated the preferred embodiment of the invention, 1 designates a pipe section constructed of a blank of sheet metal or other suitable material of the desired dimension and gauge, having one of its longitudinal edges outset at 2 and bent upon itself twice, forming an outer wall 3, an intermediate wall 4, and an inner wall 5. The outer wall 3 and the intermediate wall 4 are connected by a bead 6 and the intermediate wall 4 and the inner wall 5 are connected by a bead 7 of greater size or amplitude than the bead 6 and located at the inner face of the outset portion 2. By providing the bead 7 of greater size or amplitude than the bead 6, the intermediate and inner walls converge and gripping edges are provided at the entrance of the groove. 55 The intermediate wall 4 and the inner wall 5 converge toward each other and form an out-

wardly opening groove 8 and before closing of the seam the space 9 between the inner wall and the intermediate wall at the open end of the longitudinal groove 8 is of a width less than the thickness of the metal of the plain edge portion 10 of the seam. As the distance between the intermediate wall 4 and the inner wall 5 at the space or entrance 9 is less than the thickness of the metal of the plain edge portion 10, the walls 4 and 5 of the groove will be spread or forced apart when the plain edge portion 10 is forced between said walls 4 and 5 and will be frictionally gripped by the same for preliminarily closing the seam prior to engagement of the coacting locking devices, hereinafter described, which lock the seam closed.

The inner wall 5 is provided with an extension 11 projecting transversely beyond the groove and curved slightly inwardly and forming a guide for facilitating the introduction of the plain edge portion 10 into the groove and enabling the plain edge portion to deflect readily the inner wall 5 of the groove. This preliminary engagement of the seam members prior to locking the same positively in fully closed position, enables a plurality of pipe sections to be assembled and fitted into the position they are to occupy prior to locking the seam members in fully closed position. This greatly facilitates the handling, cutting and positioning of pipe sections to provide a pipe assembly for any desired location. The preliminary engagement of the seam members enables the pipe sections to be handled in the customary manner and fitted together and even dropped, without the plain edge portion becoming disengaged or separated from the groove of the other edge portion.

One end 12 only of the pipe section is crimped, tapered and slightly reduced in diameter to enable it to be fitted in the conventional manner within the uncrimped end of a similar pipe section to assemble the pipe sections, and the pipe section 1 is provided adjacent the crimped portion 12 with a cylindrical stiffening or reinforcing bead 13.

While the pipe section may be of any desired length it is designed to be of a standard customary length of approximately 24 inches with 2 inches at one end for the crimping of the pipe section and the formation of the reinforcing bead 13.

The plain edge portion 10 is provided with end and intermediate locking detents 14 formed by slitting the sheet metal at 15 and indenting and deflecting the sheet metal at the slit to form the detent 14 which has an inclined or beveled front face 16 and an inner or rear shoulder 17. The inner wall 5 of the other seam member is provided inwardly of the extension 11 with a slot 18 of a size to receive the detent 14 which, when the seam members are completely closed, projects through the slot 18 with its shoulder 17 in engagement with the outer end wall of the slot 18. When the detent 14 is engaged with the slot 18, the seam members are securely locked against separation.

The inner wall 5 is also provided outwardly beyond the slot 18 with a countersink 19 which is arranged to receive and guide the detent 14 during the preliminary positioning of the seam members. The countersink 19 prevents the detent 14 from offering any resistance to the preliminary positioning of the seam members and the detent is arranged in the countersink while the seam members are preliminarily engaged

with each other prior to complete locking of the seam. After the assembly of the pipe sections and the proper positioning of the same, the detent 14 is forced inwardly beyond the countersink 19 and into engagement with the slot 18. The bottom of the countersink is inclined at its inner portion to enable the detent to ride readily over the intervening portion of the inner wall 5 between the countersink and the slot 18.

- 10 The pipe section is provided with end and intermediate locking devices consisting of the detent 14 and the slot 18, as clearly illustrated in Figs. 1 to 3, inclusive, of the drawing. The end locking devices are designed to be located approximately one-half inch from the ends of the pipe section and the intermediate locking devices, which are preferably three in number but which may be of any desired number, are designed to be spaced apart 5½ inches. This location of the locking devices has been found practical and adequate and will enable the pipe section to be cut to provide a shorter pipe section which may be varied in length and which, when cut, will be provided adjacent each end with the coacting locking devices.

The seam member which is provided with the outwardly facing groove may be formed on the conventional roller machine and the coacting locking means for securing the seam members in their closed position may be die-cut and punch-pressed or formed in any other desired manner.

I claim:

- A pipe section constructed of sheet material and having opposed longitudinal edge portions, 35 one of the longitudinal edge portions being plain, the other longitudinal edge portion being rearwardly folded upon itself and then folded forwardly upon said first fold, forming an intermediate wall and an inner wall, the intermediate 40 and inner walls forming an outwardly opening groove to receive the other opposed plain edge portion, the entrance to the groove being of a width less than the thickness of said plain edge portion for preliminarily gripping the same, said 45 inner wall having an extension projecting forwardly beyond the entrance to the groove and arranged to guide the plain edge portion into the groove to effect a preliminary closing of the seam, said inner wall being provided rearwardly 50 of the entrance to the groove with a slot and having a countersink located forwardly of and adjacent the entrance to the groove in alignment with said slot, and the plain edge portion being provided on the inner side thereof with a detent 55 that is adapted to be received within the countersink, the detent being engaged with the countersink and thereby guided and aligned with said slot in the preliminary engagement of the plain edge portion with the walls of the groove, the 60 detent engaging the slot upon further inward movement of the plain edge portion within the groove.
